(57) **CLAIM**

The ornamental design for an unbanded battery case for a mobile device, as shown and described.

DESCRIPTION

FIG. 1 is a three-quarter perspective view of an unbanded battery case for a mobile device showing the new design, with the mobile device removed for clarity and illustration;

FIG. 2 is a three-quarter rear perspective view thereof;

FIG. 3 is a front view thereof;

FIG. 4 is a rear view thereof;

FIG. 5 is a left-side view thereof;

FIG. 6 is a right-side view thereof;

FIG. 7 is a bottom view thereof;

FIG. 8 is a top view thereof;

FIG. 9 is a three-quarter perspective view of an unbanded battery case for a mobile device, with the mobile device included therein;

FIG. 10 is a three-quarter rear perspective view of FIG. 9 thereof;

FIG. 11 is a front view of FIG. 9 thereof;

FIG. 12 is a rear view of FIG. 9 thereof;

FIG. 13 is a left-side view of FIG. 9 thereof;

FIG. 14 is a right-side view of FIG. 9 thereof;

FIG. 15 is a bottom view of FIG. 9 thereof;

FIG. 16 is a top view of FIG. 9 thereof;

FIG. 17 is a three-quarter perspective view of an unbanded battery case for a mobile device, containing a mobile device with the bottom portion shown in a disconnected position;

FIG. 18 is a three-quarter rear perspective view of FIG. 17 thereof;

FIG. 19 is a front view of FIG. 17 thereof;

FIG. 20 is a rear view of FIG. 17 thereof;

FIG. 21 is a left-side view of FIG. 17 thereof;

FIG. 22 is a right-side view of FIG. 17 thereof;

FIG. 23 is a bottom view of FIG. 17 thereof; and,

FIG. 24 is a top view of FIG. 17 thereof.

The portions in broken lines in the drawings are shown to illustrate environment only and form no part of the claimed design.
